UNITED STATES PATENT OFFICE

LEONARD PASSANO, OF BALTIMORE, MARYLAND, ASSIGNOR, BY MESNE ASSIGNMENTS,
TO THE CITIES ILLUMINATING COMPANY, OF NEW YORK, N. Y., A CORPORATION
OF NEW YORK.

PILOT-BURNER.

1,321,547.

Specification of Letters Patent. Patented Nov. 11, 1919.

Application filed February 3, 1917. Serial No. 146,389.

To all whom it may concern:

Be it known that I, LEONARD PASSANO, a citizen of the United States, residing at Baltimore city, and State of Maryland, have invented certain new and useful Improvements in Pilot-Burners, of which the following is a specification.

This invention relates to improvements in pilot burners for street and other lamps, and 10 more particularly to a pilot which is termed a "glower" pilot, or one in which a small quantity of material capable of being readily brought to a state of incandescence is employed in close proximity to the main or 15 lighting mantle.

One object of the invention is to provide a pilot of extremely low gas consumption, and so arranged and constructed as to remain lighted under various draft and pressure variation stresses, which are incident to 20 the use of devices of this character.

A further object of the invention is to provide a pilot which will keep, in a state of constant incandescence, a limited portion or 25 area of the main mantle from which, and consequently indirectly, the remaining portion of the main mantle is brought quickly to the desired state of incandescence which characterizes it when the light is burning, 30 and from which portion of the main mantle the gas is kindled to bring the mantle to a complete state of incandescence, without the mantle-disrupting force incident to igniting or kindling the gas after a considerable 35 quantity has accumulated within and around the mantle.

Another object of the invention is to so construct the pilot burner that the mantle fabric on the top thereof will hold the flame even at very low gas pressure, while at the 40 higher pressures, the extending glow from the pilot is caught and held by the main mantle itself, thus automatically increasing and diminishing the incandescent area of 45 the main mantle, according to the variation in the gas pressure. This insures not only a constant condition of incandescence for bringing the main mantle to a full state of incandescence, but brings about a condition 50 wherein the pilot itself has great draft resisting properties. Furthermore, by spreading the pilot glow over the surface of the mantle, the high resulting temperature insures complete combustion without carbonization on the surface of the mantle.

A still further object of the invention is to provide the pilot burner with an opening so positioned as to protect it against clogging by particles either from within or without and the location of the pilot with relation to the mantle and chimney is such that the mantle and chimney can be removed and replaced, without interference with or destruction of the pilot.

I am aware that it is not new to project a flame jet from a pilot burner laterally against a mantle but such an arrangement has such distinct disadvantages as to preclude its practical use, one of the main objections being that such a flame jet does not spread 65 over the mantle surface sufficiently to become thoroughly mixed with the air and consequently tends to deposit carbon on the mantle. Furthermore, the concentration of a jet on a small spot of the mantle fabric, 70 tends to weaken the mantle in a limited area by the impulses of the flame and causes over-hardening at and around the point of contact.

In the drawings,

Figure 1 is a side elevation of a burner showing the improved pilot in connection therewith;

Fig. 2 is an enlarged sectional view of the upper part of the pilot or tip, showing 85 the manner of attaching the incandescent filament, and the manner of forming the gas outlet opening.

Referring to the drawings, in which there is shown a burner of the type adapted to 90 receive the pilot, the numeral 1 designates the gas cock, which may be of any approved construction, 2 the gallery and 3 the Bunsen tube.

3' designates the mantle supported over 95 the burner in the usual way and 3" designates the glass shade.

The numeral 4 designates the pilot tube let into the gas supply pipe at 5, below the cock, the opening and closing of which cock 100 does not affect the supply of gas to the pilot tube, the burner being of the type or kind in which the pilot burns constantly.

The upper portion of the pilot tube is surrounded by a wrapping of incandescent 105 filament 6. The tube is better shown in Fig. 2 of the drawing, is provided with a recess 7, thus forming a contracted portion into which a part of the incandescent filament is bound by a suitable tie 8. Above the re- 110

cess, I provide the gas outlet orifice 9 through which gas constantly issues and after being once ignited, keeps the pilot filament in a constant state of incandescence or glow, and 5 the heat therefrom is imparted to an area of the main mantle, as indicated at *a* and heats said area to a state of incandescence which constantly remains in such state and in readiness to ignite the main body of the 10 mantle when the exigencies of use require it. I thus provide two incandescent surfaces for holding the lighting glow which is found in practice to be particularly advantageous as it provides against disadvantages resulting from gas pressure variations.

It will be noted that the outlet of the 15 pilot tube is so positioned that draft conditions become of little consequence, as variation in drafts in the present arrangement, 20 do not materially affect the glow of either the mantle fabric or the pilot or the material of the mantle.

The arrangement described, by which a 25 portion of the mantle is kept in a constant state of incandescence, insures the immediate kindling of the gas as it comes into the burner, preventing the possibility of accumulations, which, with the use of ordinary 30 pilot burners is suddenly kindled and in fact exploded, with a disruptive force very injurious to the mantle. In other words, the mode of operation of kindling or lighting the gas in the burner, I have described, is utterly different from that characterizing 35 any pilot burner of which I am aware, in that the pilot described is the indirect means by which the gas is kindled. Furthermore, the provision of the fuel outlet in the pilot 40 burner produces the glow of the incandescent material of the top of the pilot, at a point where it is communicated to the mantle to keep a considerable portion thereof in an incandescent state, and this arrangement of fuel outlet has a very distinct ad- 45 vantage from a point of economy in shades very commonly used in burners of this type, in that the side of the pilot opposite the discharge opening is comparatively cool, and does not therefore, communicate a danger- 50 ous amount of heat to the glass adjacent to the pilot burner, which heat on the shade not being balanced uniformly throughout the entire periphery of the shade, causes considerable breakage of the glass, due to 55 varying temperatures. Especially is this true when the main mantle is not in a state of incandescence.

Having thus described my invention, what I claim is:

60 1. The combination with an incandescent mantle, of a pilot tube adjacent thereto and

supporting a filament of incandescent material out of contact with the mantle, but near enough thereto to communicate a heat glow to a portion of the mantle, whereby 65 said portion is kept in a state of constant incandescence, said incandescent portion serving to kindle the gas to bring the entire mantle to a state of incandescence.

2. The combination with an incandescent 70 mantle of a pilot tube adjacent thereto and having a discharge opening in the side and supporting a filament of incandescent material out of contact with the mantle, but near enough thereto to communicate a heat glow 75 to a portion of the mantle, whereby said portion is kept in a state of constant incandescence, said incandescent portion serving to kindle the gas to bring the entire mantle to a state of incandescence.

3. The combination with an incandescent 80 mantle, of a pilot tube adjacent thereto, and having the gas discharge opening in the side adjacent the mantle, and supporting a filament of incandescent material out of 85 contact with the mantle, but near enough thereto to communicate a heat glow to a portion of the mantle, whereby said portion is kept in a state of constant incandescence, said incandescent portion serving to kindle 90 the gas to bring the entire mantle to a state of incandescence.

4. The combination with an incandescent 95 mantle, of a pilot light adjacent thereto and having the gas discharge opening in the side adjacent the mantle and having a filament of incandescent material wrapped therearound over the gas discharge opening to form a heat glow and communicate it to a portion of the mantle, whereby said portion is kept in a state of constant incandescence.

5. The combination with an incandescent 100 mantle, of a pilot light tube adjacent thereto and having a closed upper end and a gas 105 discharge opening in the side adjacent the mantle, the said tube having a recess below the gas opening, a filament of incandescent material wrapped around the tube opposite the recess and extending above the end of the tube, and a tie for holding the filament in the recess around the tube, said incandescent filament forming a heat glow and communicating it to a portion of the mantle, whereby said portion is kept in a state of 110 constant incandescence.

In testimony whereof I affix my signature in presence of two witnesses.

LEONARD PASSANO.
